UNITED STATES PATENT OFFICE

CHARLES L. SKELLEY, OF NEW YORK, N. Y.

RAZOR STROP AND CASING

Application filed June 9, 1925. Serial No. 36,048.

My invention relates to a razor strop and more particularly to a combination razor strop and casing arranged to hold not only the strop but a razor therein.

5 One of the disadvantages involved in using a razor of the type which has to be stropped is the necessity for carrying a strop as well as a razor with one on his travels. Also, a razor is not a safe thing to carry around, 10 and it is highly desirable that one have a simply formed casing arranged to carry the razor and that a strop be combined with this in some way to avoid the inconvenience of carrying two separate objects.

15 It is accordingly the main purpose of my invention to meet this difficulty and to provide a combination razor strop and casing which will serve not only as a strop but will carry a razor therein properly protected and 20 ready for use at any time.

It is another object of my invention to provide a very simple and inexpensive construction in which the razor strop and its casing are fastened together so that they cannot be 25 separated and in which the casing will serve to hold not only the razor but the strop as well and so protect the latter from dust and keep it from contacting with other objects when being carried in one's hand bag or toilet 30 kit.

With these and other objects in view, as will be apparent to one skilled in this art, my invention resides in the combination of parts set forth in the specification and 35 covered by the claims appended hereto.

In accordance with my invention, I propose to form a casing which has the strop fastened thereto. This casing is arranged to hold the strop therein, preferably folded so as to make it unnecessary to use a long casing, and the parts are so arranged that a razor or other objects may be placed within the casing adjacent to the strop. I preferably form this 40 casing of a strip of leather or other suitable flexible material which has an open side and is so arranged that the strop may be slid edgewise into the casing or drawn out and arranged to be hung on a wall in an operative position. The casing is preferably provided with a flap arranged to cover the open

side and fasteners may be provided to secure the flap in place whereby the razor and strop will not fall out of the casing. My preferred manner of fastening the strop within the casing involves forming the casing with an open 55 end as well as the open side and pivotally fastening one end of the strop to a wall of the casing adjacent to said open end, the pivotal fastening being so constructed and arranged that the strop may be swung outwardly so that 60 when the strop is hung on the wall the casing will serve as a handle to hold the strop during operative use, or will hang on the strop end if the operator prefers to grip the strop while 65 stropping the razor.

Referring to the drawing, I have there shown a perspective view of one simple embodiment of this invention.

As illustrated, the razor strop 10 may be formed of a strip of leather having suitable 70 surfaces on its sides for stropping and sharpening a razor, but it may be otherwise constructed in accordance with the usual arrangements heretofore employed for this purpose. A simple form of casing arranged to 75 hold a razor and the strop may be formed of suitable flexible material such as leather or the various leather substitutes or canvas materials. The main body of the casing may be simply formed of a single strap of flexible 80 material bent along an edge 12 to form a short side 13 and a longer side 14. The two sides 13 and 14 are stitched together at the edge 15 to form a casing which is open at the side 16 and adjacent to the end 17. That portion 85 of the side 14 which projects beyond the side 13 is arranged to be bent back in order to form a flap or closure to hold objects within the casing. If desired, this flap may be bent over the outside of the casing and secured 90 thereto by suitable means, such as the snap fasteners which comprise eyelets 20 and flexible projecting members 21 arranged to be inserted within the openings of the eyelets to engage with the peripheries thereof as is well 95 understood in this art.

This casing is preferably made of such a length that when the strop is bent double it will slip edgewise neatly into the casing and allow room for carrying a razor within 100

the folds of the razor strop. While the strop 10 may be suitably fastened to the casing by various means, I preferably make use of the very simple construction illustrated which 5 comprises a pivotal connection so arranged that the strop may be swung outwardly or folded into the casing without disconnecting it therefrom. For this purpose I make use of a simple rivet fastener 22, which may 10 be of any suitable type as is well known in the leather working industry. The stropping member 10 is so mounted on this fastener that it may readily turn edgewise about it as a pivot, and it will be seen that the shapes of 15 the parts are such that the strop may be swung out so that it forms substantially an extension of the main body of the casing.

In order that the stropping member 10 may be suitably supported on a wall, I provide it with an eyelet 24 or other suitable means whereby it may be hung over a hook and suspended therefrom. When hanging in such a position, the flap may be folded over the main body of the casing and thereby 25 form a handle of substantially the same width as the razor strop, whereby the latter may be held securely and firmly in one hand and the razor securely stropped thereon.

While the casing will serve as a container 30 for various types of razors, I have illustrated it is particularly adapted for holding a razor of the form shown in my prior Patent No. 1,635,642. This razor is of the hoe type, but the blade is pivotally mounted so 35 that it may be swung into a stropping position. After this razor 25 has been stropped with the blade in the position illustrated it may be placed in the fold of the strop before or after the strop has been turned on its 40 pivot and moved into the casing. When the parts are in place, the flap is then bent over and the eyelet fasteners secured. The pivotal fastener 22 prevents the razor from escaping through the end of the casing, but if 45 desired, a suitable flap may be provided to close this end also and more securely hold the razor in place.

The advantages inherent in this construction 50 will be obvious from the above disclosure and it is to be understood that this device may be suitably modified within the scope of the appended claims and the knowledge of one skilled in the art.

Having thus described my invention, what 55 I claim as new and desire to secure by Letters Patent is:—

1. A razor strop comprising a casing of 60 flexible material which is open only at one end and one side, a flexible leather stropping member pivotally connected to a wall of the casing at said open end in such a manner that it may swing edgewise into the casing and be concealed therein or it may be swung 65 around to form an extension of the casing

whereby the latter serves as a handle for the strop, and a flap on the casing arranged to enclose the open side of the casing, said casing being arranged for the insertion of a razor through the open side and permitting 70 both the razor and the strop to be safely carried therein.

2. A razor strop comprising a sheet of 75 flexible material folded on itself and secured to form a casing having an open side and an open end and a flap arranged to fold over so as to form a casing for a razor, and a flexible leather stropping member pivotally mounted adjacent to the open end of the casing and arranged to be folded and inserted within the casing or to swing edgewise outwardly therefrom and serve as an extension of the casing whereby the latter forms a handle when the stropping member is used.

3. A razor strop comprising a sheet of 80 flexible material folded on itself to form a casing having an open end, an open side and a flap arranged to fold over the open side, fasteners arranged to secure the flap to the casing to form an enclosure to hold a razor therein, and a leather stropping member pivotally mounted on the casing adjacent to the open end and arranged to be folded and inserted edgewise into the casing or to swing outwardly to strop a razor.

Signed at Worcester, Massachusetts, this 90 5th day of June, 1925.

CHARLES L. SKELLEY.
